UNITED STATES PATENT OFFICE

138,102

DESIGN FOR AN AIRPLANE

Allan O. Kelly, Carlsbad, Calif.

Application May 31, 1943, Serial No. 110,336

Term of patent 7 years

(Cl. D71—1)

To all whom it may concern:

Be it known that I, Allan O. Kelly, a citizen of the United States of America, residing at Carlsbad, in the county of San Diego and State of California, have invented a new, original, and ornamental Design for an Airplane, of which the following is a specification, reference being had to the accompanying drawings, forming part thereof.

Figure 1 is a front elevational view of an air-

plane showing my new design; Fig. 2 is a top plan view thereof; Fig. 3 is a side elevational view thereof and Fig. 4 is a bottom plan view of a fragmentary portion showing one of the tail gun turrets.

I claim:

The ornamental design for an airplane, substantially as shown.

ALLAN O. KELLY.
